UNITED STATES PATENT OFFICE.

WILLIAM DEMUTH, OF NEW YORK, N. Y.

DESIGN FOR A TOBACCO-PIPE.

SPECIFICATION forming part of Design No. 24,029, dated February 12, 1895.

Application filed January 15, 1895. Serial No. 535,036. Term of patent 7 years.

To all whom it may concern:

Be it known that I, WILLIAM DEMUTH, a citizen of the United States, residing at New York, in the county and State of New York, 5 have invented and produced a new and original Design for Tobacco-Pipes, of which the following is a specification.

My design is illustrated in the accompanying drawing which represents a perspective 10 view of a tobacco pipe showing my design.

The leading feature of my design is the figure of a man stretched upon the stem of the tobacco pipe and touching with one hand the bowl.

15 The letter A designates the stem of my tobacco pipe and B is the bowl. The bowl rises from the stem in the form of a globe.

C is the figure of a man stretched upon the stem with his back up, the feet being extended toward the mouth-piece of the stem while one 20 hand is in contact with the bowl and the head is raised as shown.

What I claim as new, and desire to secure by Letters Patent, is—

The design for a tobacco pipe substantially 25 as herein shown and described.

In testimony whereof I have hereunto set my hand in the presence of two subscribing witnesses.

WILLIAM DEMUTH.
